OTHER PUBLICATIONS

Photos of co-molded chuck believed to be sold more than 1 year prior to the filing date of the present application, prior to Jul. 11, 2005.

Primary Examiner—T. Chase Nelson

(74) Attorney, Agent, or Firm—Nelson Mullins Riley & Scarborough, LLP

CLAIM

The ornamental design for a drill chuck, substantially as shown and described.

DESCRIPTION

FIG. 1 is a perspective view of a drill chuck embodying my new design of the present invention;

FIG. 2 is a front elevation view of the drill chuck illustrated in FIG. 1;

FIG. 3 is a back elevation view of the drill chuck shown in FIG. 1;

FIG. 4 is a left side view of the drill chuck shown in FIG. 1;

FIG. 5 is a right side view of the drill chuck shown in FIG. 1;

FIG. 6 is a top view of the drill chuck shown in FIG. 1; and, FIG. 7 is a bottom view of the drill chuck shown in FIG. 1. Broken lines are for illustrative purposes only and form no part of the claim.
